Primary Examiner — Catherine S Posthauer*Assistant Examiner* — Joan E. Diehl(74) *Attorney, Agent, or Firm* — Alumen IP Law PC(57) **CLAIM**

The ornamental design for a bottle with bumper, as shown and described.

DESCRIPTION

FIG. 1 is a top perspective view of a bottle with bumper embodying my new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The stippling shown in the drawings indicates a contrast in surface appearance.
